INVENTOR.

BY G. B. MEAD
Victor J. Evans
ATTORNEY

UNITED STATES PATENT OFFICE.

GEORGE B. MEAD, OF SAN FRANCISCO, CALIFORNIA, ASSIGNOR OF ONE-FOURTH TO
JULIUS GRIFFIN, OF SAN FRANCISCO, CALIFORNIA.

GUN.

Application filed March 29, 1924. Serial No. 702,969.

To all whom it may concern:

Be it known that I, GEORGE B. MEAD, a citizen of the United States, residing at San Francisco, in the county of San Francisco and State of California, have invented new and useful Improvements in Guns, of which the following is a specification.

This invention relates to improvements in guns and has particular reference to a spring gun employing preferably a rubber band.

The principal object of this invention is to produce a gun which is simple to operate, yet powerful in action.

Another object is to produce a gun where-
in the propulsive force may be readily ad-
justed to meet the requirements of the opera-
tor.

A still further object is to produce a gun wherein the same may be manufactured at a reasonable cost.

Other objects and advantages will be ap-
parent during the course of the following description.

In the accompanying drawings forming
a part of this specification and in which like
numerals are employed to designate like
parts throughout the same,

Figure 1 is a side elevation of my gun,

Figure 2 is a top plan view of Figure 1,

Figure 3 is an enlarged end elevation,

Figure 4 is a detail view of the combined
guide and stop,

Figure 5 is a side elevation of Figure 4,

Figure 6 is an enlarged detail cross sec-
tion of the ammunition carrier,

Figure 7 is a side elevation of a modified
form of my gun showing a knock-down
feature,

Figure 8 is an enlarged detail view of the
spring fastening clip, and

Figure 9 is an enlarged detail cross sec-
tion of the releasing mechanism.

Many forms of guns have been devised
which employ an explosive propulsive force,
air propulsive force and spring propulsive
force. I have sought to improve upon the
spring type and by viewing the figures it
will be noted that the numeral 5 designates
the customary butt having a stock 6 which
customarily holds the barrel.

This stock has a groove 7 formed in its
upper surface and extending the entire
length thereof. Within this groove is posi-
tioned an ammunition carrier 8 having a

bore 9, and carrying a sight 11 upon its 55
upper surface.

At 12 I have shown a rubber resilient
band having its ends fastened to the eyes
13 and 14 of the spring fastening clip 16,
which is substantially U-shaped and is 60
adapted to be retained in one of the inclined
slots 17. The center portion of the rubber
band 12 passes through an opening 18
formed in the ammunition carrier and is
guided through the eyes 19 and 21 of the 65
stop 22. This stop is adapted to be retained
in one of the slots 23 formed in the under
surface of the stock 6.

A spring prong 20 is formed integral with
the stop 22 and extends upwardly into the 70
body of the stock 6, the purpose of which
will be later seen. Pivoted to each side of
the stock are hooks as shown at 24 and 26.
These hooks are pivoted as at 27 and 28,
respectively and normally contact with pins 75
29 and 31, respectively, these hooks being
kept in contact with their respective pins
as by a spring 32.

The release mechanism is best shown in
Figure 9 where it will be noted that a trigger 80
33 is pivoted as at 34 within a recess 36
formed in the stock 6. This trigger has a
nose 37 adapted to engage the nose 38 of a
catch 39 pivoted at 41 and normally held in
elevated position by a spring 42.

A dog 43 is formed upon this catch, which
dog is adapted to enter a recess 44 formed
in the under-surface of the ammunition car-
rier. This recess is provided with a metal
liner 46 for the purpose of preventing undue
wear through contact with the dog.

A disappearing sight 47 is supported upon
a V-shaped member, which is pivoted at 48
and 49 near the end of the gun. A spring
51 is formed integral with the V-shaped 95
member and has an inturned end 52 adapted
to enter a suitable recess in the gun. A
controlling link 53 extends from the V-
shaped member rearwardly and is connected
as at 54 to the band 12.

In the view shown in Figure 7, the con-
struction is identical with the exception that
the butt 5 and the stock 6 are made separate-
ly so that the gun may be folded. These
parts are joined together as by a lug 56 en-
tering a suitable recess in the stock 6 after
which a pin is inserted at 57, which pin will
pass through the lug 56.

A pin 58 is also adapted to engage an opening 59 in the stock for the purpose of further locking the parts together.

The operation of my gun is as follows:—

- 5 The operator inserts ammunition within the bore 9 of the ammunition carrier 8 after which time the carrier is manually moved toward the butt or until the recess 44 is engaged by the dog 43. This causes the band 12 to stretch a considerable distance and remain stretched until the trigger is released. The stretching of this band also causes the sight 48 to be moved up into its vertical position as best shown in Figure 3. Should it 10 be desired to lock the ammunition carrier in the cocked position, that is, just before it is engaged by the dog, the operator moves the hooks 24 and 28 upwardly so as to bring the points between the ammunition carrier 20 and the band at the point slightly in front of the opening 18, thus locking the ammunition carrier in a retracted position. As soon as the ammunition carrier is moved toward the butt the spring 20 of the stop 22 will 25 cause the stop to move from the dotted line position in Figure 5, to the full line position, with the result that the rubber band may slide through the eyes 19 and 21 without substantial contact therewith, thus reducing wear.

This construction also brings the ammunition carrier to a more gradual stop than if it were to strike a solid stop, which would result in a short life to the gun. When it 35 is desired to vary the propulsive force, the band retainer 16 may be moved to one of the other inclined slots 17 and the stop 22 may also be moved to one of its other slots.

It will thus be seen that I have provided 40 a gun with many adjustments, yet one which is simple and one which will simulate the ordinary gun in its action.

It is to be understood that the form of my 45 invention herewith shown and described is to be taken as a preferred example of the same and that various changes in the shape, size and arrangement of parts may be re-

sorted to without departing from the spirit of the invention or the scope of the subjoined claims.

Having thus described my invention, I claim:—

1. In a gun, a stock having a groove formed therein, an ammunition carrier adapted to be reciprocated on the groove, a ⁵⁵ U-shaped spring fastening clip adjustably secured to said stock, a spring secured to said clip and engaging said ammunition carrier, a U-shaped stop adapted to straddle said stock, eyes formed in said U-shaped stop and adapted to encircle said band on opposite sides of said carrier, a spring formed integral with said stop and adapted to enter into said stock, a V-shaped member pivoted to said stock, a link connected to said V- ⁶⁰ shaped member and to said band for moving said V-shaped member to a vertical position when said band is under tension, and means for releasing said carrier, for the purpose specified.

2. In a gun, a stock having a groove formed therein, an ammunition carrier adapted to be reciprocated on the groove, a ⁶⁵ U-shaped spring fastening clip adjustably secured to said stock, a resilient band secured to said clip and engaging said ammunition carrier, a U-shaped stop adapted to straddle said stock, eyes formed in said stop and adapted to encircle said spring on opposite sides of said carrier, a spring formed integral with said stop and adapted to enter into said stock, a V-shaped member pivoted to said stock, a link connected to said V- ⁷⁰ shaped member and to said band for moving said V-shaped member to a vertical position when said band is under tension, means for releasing said carrier, said means comprising a pivoted trigger mounted within said stock, a spring pressed latch adapted to be actuated by said trigger, and a dog formed on said latch and adapted to enter a recess formed in said carrier.

In testimony whereof I affix my signature.

GEORGE B. MEAD.
